UNITED STATES PATENT OFFICE.

ARNOLD W. ZIMMERMAN, OF FERNWOOD, ASSIGNOR OF ONE HALF TO
JAMES S. TOPPAN, OF CHICAGO, ILLINOIS.

GAS-FIXTURE.

SPECIFICATION forming part of Letters Patent No. 363,787, dated May 24, 1887.

Application filed November 27, 1886. Serial No. 229,016. (No model.)

To all whom it may concern:

Be it known that I, ARNOLD W. ZIMMERMAN, a citizen of the United States, residing at Fernwood, in the county of Cook and State 5 of Illinois, have invented certain new and useful Improvements in Gas-Fixtures, which are fully set forth in the following specification, reference being had to the accompanying drawings, forming a part hereof, and in which—
10 Figure 1 shows my improved fixture in perspective. Fig. 2 shows the essential or working parts of the same in sectional elevation.
Like letters refer to like parts.

The object of my invention is to provide a 15 means whereby the gas may be turned on and off the burners without being obliged to reach over the burner or shade, or to have chains dependent from the cock for such purpose, which are both unsightly and annoying, as well as expensive. To accomplish said end I construct 20 my fixture as follows, namely:

I provide a flanged socket-piece, *f*, which is 25 threaded so as to screw to the pendent pipe *a* in the same hole which forms the seat of the plug *b*. Said socket-piece is formed with a shank, *e*, having a conical bore, which forms the seat of the hollow plug *b*, and said plug projects at the lower end of the socket at least a sufficient distance to permit a suitable attachment, as a bar, *j*, to be attached to it so as 30 to serve as a stop for the plug in turning, although said stop might also be at the upper end of the plug, and by means of said bar *j* the plug may be turned; or, if preferred, the 35 end of the plug may be adapted for a key with which it may be turned. The end of the shank *e* terminates in a spur, *l*, which forms a stop, against which the bar *j* or other suitable spur strikes as the plug is turned. Said plug is

provided with a cavity, *k*, and through the 40 side of the plug are bored one or more holes, *c*, which fit over corresponding holes in the side of the shank *e*, so as to allow the gas to enter into the annular chamber *d*, formed around the shank *e* by means of the shell *g*, 45 which is screw-threaded at its lower end to fit the threaded end of the shank *e*, and its upper end fits against the shoulder of the socket-piece *f*, so as to form a gas-tight joint. Into said shell *g* are inserted pipes *h*, carrying sockets *i*, which receive the burner-tips.

By this construction it will be seen that the cock is below instead of above the burners, and is far more convenient to reach and manage, and by the conical form of the plug it will 55 by its own weight tend to keep tight, and will not be affected by the heat of the burners. By means of the shell *g* and flange *f* the annular chamber *d* forms a reservoir for the gas received through the opening *c*.
60

What I claim is—

1. A gas-fixture formed of a flanged socket-piece, *f*, having a central shank, *e*, in combination with a shell, *g*, forming with said flange the chamber *d*, and a plug and openings from 65 it into said chamber, substantially as specified.

2. A gas-fixture formed of a flanged socket-piece, *f*, having a central shank, *e*, provided with a conical bore largest at its upper end, in combination with a hollow conical plug provided with lateral openings fitting over corresponding holes in the shank *e*, and a shell, *g*, forming with flange *f* a chamber, *d*, substantially as specified.
